(57) **CLAIM**

The ornamental design for a butt stock, as shown and described.

DESCRIPTION

FIG. 1 is right isometric perspective view of a butt stock, showing my new design.

FIG. 2 is a left isometric perspective view thereof.

FIG. 3 is right side elevational view thereof.

FIG. 4 is a left side elevational view thereof.

FIG. 5 is a bottom plan view thereof.

FIG. 6 is a top plan view thereof.

FIG. 7 is rear elevational view thereof; and,

FIG. 8 is front elevational view thereof.

The broken lines in the drawings depict portions of a firearm having the butt stock and form no part of the claimed design.
